UNITED STATES PATENT OFFICE.

HENRY J. PLANT, OF ROCHESTER, NEW YORK, ASSIGNOR TO DEFIANCE CHECK WRITER CORPORATION, OF ROCHESTER, NEW YORK, A CORPORATION OF NEW YORK.

PRINTING APPARATUS.

1,358,461.

Specification of Letters Patent.

Patented Nov. 9, 1920.

Application filed December 23, 1916. Serial No. 138,573.

To all whom it may concern:

Be it known that I, HENRY J. PLANT, a citizen of the United States, and resident of Rochester, in the county of Monroe and 5 State of New York, have invented certain new and useful Improvements in Printing Apparatus, of which the following is a specification.

The present invention relates to printing apparatus and more particularly to the type which is adapted to print various amounts in gas, water and electric bills to correspond to the service used, an object of 10 this invention being to provide a construction which is compact in form and yet will permit the making of a bill for a minimum service, a maximum service, or any service therebetween.

To this and other ends, the invention 15 consists of certain parts and combinations of parts all of which will be hereinafter described, the novel features being pointed out in the appended claims.

In the drawings:—

20 Figure 1 is a plan view of a machine embodying the present improvements;

Fig. 2 is a vertical section through the machine in the direction of the axis of the printing cylinder;

25 Fig. 3 is a vertical transverse section on the line *a*—*a*, Fig. 2;

Fig. 4 is a section on the line *b*—*b*, Fig. 1;

Fig. 5 is a section on the line *c*—*c*, Fig. 1;

30 Fig. 6 is a longitudinal section through one of the platens; and

Fig. 7 is a transverse section through one of the platens.

Referring more particularly to the drawings, 1 indicates a casing having a bottom

40 1^a hinged thereto at 3^a and secured in closed position by a latch 4^a. Within the casing a shaft 2 is mounted, this shaft having thereon two printing wheels 3 and 4, each, in this instance, having two peripheral series of

45 type 5 and 6, one series on each wheel serving to print on the body of the bill and the other series serving to print on the stub of the bill. The wheel 3 has its characters running from the smallest amount for which

50 a bill is rendered, while the wheel 4 has its characters running from an amount next in order to that of the highest amount on the wheel 3, so that a bill may be rendered for any service between the lowest on the wheel

3 to the highest on the wheel 4. The printing wheel 3 is detachably secured to the shaft 2 by a pin 7 which causes the wheel 3 to turn with the shaft, and the wheel 4 is mounted to turn loosely on the shaft, being held in spaced relation to the wheel 3 by a sleeve 8 about the shaft 2. Motion is transmitted to the printing wheel 3 by a hand wheel 9 which is connected to a dial wheel 10 and is removably secured to the shaft 2 on the exterior of the casing, said shaft 2 being extended to one side of the casing 1, as shown in Fig. 2.

Motion is transmitted to the printing wheel 4 by a hand wheel 11, the latter being mounted upon one end of a hollow shaft 70 12 which receives the shaft 2 and turns in the casing 1, being projected from a gear wheel 13 arranged within the casing. This gear wheel 13 meshes with a pinion 14 and counter shaft 15 journaled within the casing and carrying a pinion 16 which meshes with a gear wheel 17 secured to the printing wheel 4. By this arrangement, when the key or pin 7 is removed, the shaft 2 may be withdrawn axially from the sleeve 12 and 80 the printing wheels 3 and 4, thus permitting the substitution of other printing wheels without removing the gear wheel 13 or the hand wheel 11. The hand wheel 11 has a cap 11^a fitting the end of the shaft 12 85 and between this cap and the casing 1, a sleeve 11^b is arranged to hold the shaft 12 against axial movement when the shaft 2 is removed. The shaft 2 does not extend to the end of the shaft 12, so that a chamber 90 11^c is provided into which oil may be introduced by way of the opening 11^d in the cap 11^a.

To the end that the dial wheel 18, which corresponds to the printing wheel 4, may be 95 located at one side of the printing machine in proximity to the dial wheel 11, the dial wheel 18 is secured to a hollow shaft 19 in which the shaft 2 turns, said shaft 19 having a gear wheel 20 thereon which meshes with 100 a pinion 21 on the counter-shaft 15. This arrangement permits the removal of the printing wheels without removing the dial 18 or the gear wheel 20. A sleeve 19^a surrounds the shaft 19 and abuts the dial wheel 105 18 at one end and the casing 1 at the other end, to hold the gear 20 in position when the shaft 2 is removed.

The top 22 of the casing is extended in front of the latter and also at opposite sides of the latter, being provided with two slots 23 each of which is over one of the printing 5 wheels 3 and 4. This top serves as a support for the work which is placed inverted on said top and is pressed downwardly through the slots 23 by a platen mechanism.

The platen mechanism, in this instance, 10 embodies two platens 24, each of which comprises a strip of rubber or other yielding material of slightly greater length than the slot 23, said rubber having a central portion adapted to pass through the slot and end 15 portions 25, adapted to rest upon the top at the opposite ends of the slot to limit the movement of the platen through the slot.

This rubber platen is preferably partially incased in a sheath 26, in this instance 20 formed of sheet metal bent in U-form, and having spring tongues 27 at its ends projecting upwardly and provided with eyes. This sheath is received within a channel in a head 28 which is carried by a plunger 29, 25 the head having pins 30 at opposite ends for entry into the eyes of the spring tongue 27, thus holding the platen and its sheath to the head 28 and preventing longitudinal movement of the platen, but permitting the ready 30 removal of the sheathed platen from the head. The plunger 29 is guided in a block 31, the block having a chamber therein for a coil spring 32 which surrounds the plunger 29, abuts the chamber at its lower end, and 35 the head 33 on the plunger at its other end.

A lever 34, pivoted at 35 to the block 31, engages the head 33 to move the platen 24 toward the printing wheel.

The two heads 31, for the two platens 24, 40 are preferably secured by screws 36 to a horizontal bar or bridge 37, which is spaced from the top surface 22 of the casing preferably by supporting arms which extend vertically at 38, thence horizontally at 39 45 under the side extensions of the top 22 to support the latter, and finally downwardly at 40, the downwardly-extended portions being screwed or otherwise fastened to the upright side walls of the casing 1.

50 The printing wheels are inked by rollers 41, the constructional arrangement of which does not enter into the present invention, and the printing lines are held centered beneath the slot 23 by centering devices 42 55 which coöperate with centering wheels 43 on the printing wheels 3 and 4. The construction of these devices do not enter into this invention.

Three gages are provided, namely, rear 60 gage 44 common to both of the printing wheels or members 3 and 4, a gage 45 for the printing member 3, and a gage 46 for the printing member 4.

The gage 44 is preferably in the form of a 65 bar resting on the top surface of the top

plate 22 and carrying headed bolts 47 at opposite ends for engaging the under side of the top plate, the top plate having slots 48 in which projections 49 on the bar operate to guide the latter when it is adjusted toward and from the slots or openings 23. 70

The gages 45 and 46 are also preferably each in the form of a bar resting on the top surface of the top plate 22, and having lugs 50 near opposite ends working in slots 51 75 which are in the top plate 22 and extend parallel with the slots or openings 23. Headed bolts 52 extend through the bars at the lugs 50 and work in the slots 51 to permit the adjustment of the bars transversely 80 in the direction of the length of the openings 23.

As before pointed out, the present embodiment of the invention is especially designed for placing in water, gas, or electric 85 bills an amount corresponding to the service furnished, each printing wheel having two series of characters thereon, one for the main body of the bill and one for the stub. The numbers on the dial do not indicate the 90 amount of the charge but are based upon a certain unit, such unit indicating, for instance, a certain number of gallons of water, a certain number of feet of gas, or a certain number of kilowatt hours of electricity. 95 This unit may be varied if it is desired to use the machine for other purposes. By having two printing members, a large range is provided without the necessity of employing a single large type wheel. Should it be 100 desired to print with the type wheel 3, the work is placed upon a table 22 against the gages 45 and 44, which have been previously adjusted to the size of the work. The platen lever 34, which moves the platen 24 105 into contact with the wheel 3, is depressed, so that a line of type on both series on the type wheel is impressed upon the bill. Should the charge call for an amount greater than is provided by the type wheel 110 3, the type wheel 4 is adjusted and the work is placed against the gages 44 and 46 after which the plate for coöperation with the type wheel 4 is operated, giving the same 115 results as those produced by the operation of the platen which coöperates with the type wheel 3.

Should it be desired to remove the type wheels 3 and 4, for the introduction of new wheels, or of wheels having different 120 amounts thereon, the pin 7 is removed permitting the withdrawal of the shaft 2 which frees both of the type wheels 3 and 4 without dismantling any other parts of the machine. 125

What I claim as my invention and desire to secure by Letters Patent is:—

1. In combination with a plurality of printing members adjustable independently about a common axis hand wheels for turn- 130

ing said members arranged at opposite sides of the machine, a plurality of independently operable platens, each for coöperation with one of the printing members in line 5 with each other, and a plurality of indicating dials lying one beside the other and each connected to one of the printing members.

2. In a printing apparatus, a casing, a printing member arranged in the casing, a top plate serving as a work support and having an opening through which a portion of the printing members is exposed, said plate being extended at opposite sides of the casing, a bridge piece spaced from said 10 top plate and having its ends extended downwardly at opposite sides of the top plate, and thence under the extended portions of the top plate and secured to the side walls of the casing.

15 3. In combination with two printing wheels mounted upon a common axis and independently adjustable, a common casing for said printing wheels having a top plate formed with two separate slots arranged in alinement and each exposing a portion of a printing wheel, two gages mounted at opposite sides of the top, one 20 for each printing wheel, a gage at the rear of the top, common to both printing wheels, and two independently operable platens, one for each printing wheel.

25 4. In combination with a casing, two gear wheels having hollow shafts journaled in opposite walls of the casing, a hand wheel 30

secured to one of said hollow shafts, a dial 35 wheel secured to the other shaft, a shaft extending into both hollow shafts, a hand wheel and a dial wheel on said shaft, two printing wheels mounted on the shaft between the two gear wheels, one of said printing wheels being secured to the shaft to turn therewith and the other being mounted to turn on the shaft, and driving connection between the gear wheels and the printing wheel which turns on its shaft.

40 5. In combination with a printing member, a casing for said printing member having an opening through which the type on the printing member are exposed, and a yielding platen having a yielding portion 45 adapted to pass through the opening to co-operate with the printing member and yielding portions for coöperating with the casing at opposite ends of the slot.

6. In combination with a grooved platen 50 head, a sheathed platen arranged in said groove, and spring latch tongues projecting from opposite ends of the platen and coöperating with the ends of the platen head to limit the longitudinal movement of the 55 platen in the groove.

7. In combination with a grooved platen head, a yielding platen, and a sheath for the platen formed of sheet metal of channel 60 form and having spring tongues bent therefrom at opposite ends of the channel to co-operate with the ends of the platen head.

HENRY J. PLANT.
